REFRIGERATING APPARATUS WITH HOT GAS DEFROSTING MEANS

Hyman Malkoff and Otto J. Nussbaum, Trenton, N. J., assignors to Kramer Trenton Company, Trenton, N. J., a corporation of New Jersey

Application August 22, 1950, Serial No. 180,774

7 Claims. (Cl. 62—117.55)

1

This invention relates to refrigerating apparatus and, more particularly, to such which includes means for periodically defrosting the evaporator that functions as the cooling or chilling unit.

It has for an object to provide such an apparatus in which there is comprised an heat holding substance, such as a fusible salt of proper crystalline form, which serves to insure thoroughly complete reevaporation of the liquid refrigerant flowing back from the evaporator to the compressor following defrosting of the former.

Another object is to provide such an apparatus in which the heat holding substance is enclosed in a casing, or the like, into which the suction conduit leading from the outlet of the evaporator to the inlet of the compressor enters to deposit the refrigerant as liquid and then recapture it in vapor form for passage to the compressor.

Another object is to provide such an apparatus in which the said suction conduit passes in heat exchange relation with the hot gas compressor discharge conduit before entering the heat holding substance casing, in order that the refrigerant fluid may attain a temperature adequate to fuse the heat holding substance.

Another object is to provide such an apparatus in which the hot gas compressor discharge conduit passes in heat exchange relation with the heat holding substance to impart heat to the latter for fusing the heat holding substance.

A further object is to provide certain improvements in the form, construction, material and arrangement of the parts whereby the above named and other objects inherent in the invention may be effectively attained.

Practical embodiments of the invention are represented in the accompanying drawing in which Fig. 1 represents a diagrammatic layout of refrigerating apparatus embodying the form of the invention in which the suction conduit leading from the outlet of the evaporator to the inlet of the compressor passes in heat exchange relation with the hot gas compressor discharge conduit before entering the heat holding substance casing; and

Fig. 2 similarly represents a modified form of the invention in which the hot gas compressor discharge conduit enters the said heat holding substance casing and passes in heat exchange relation with the said substance.

It is well known that refrigerating apparatus, particularly if designed for creating temperatures below freezing, accumulates when in operation a layer of ice on the evaporator unit that is com-

2

monly in the form of a coil of pipe provided with fins. This accumulation of ice reduces the operating efficiency of the apparatus and requires periodic removal, for the accomplishment of which a large number of arrangements or systems or means have heretofore been provided in varying forms. It is now generally recognized that provision for such periodic defrosting is not acceptable unless it is thoroughly effective in a very short time in order to avoid any substantial temperature rise in the refrigeration chamber of substantial duration. One method of defrosting involves circulation of hot gas emanating from the compressor discharge through the interior of the evaporator coil, and satisfactory accomplishment of such defrosting requires that there be an adequate quantity of heat available rapidly to perform the defrosting, and also that the hot gas which has been condensed in the evaporator during defrosting be thoroughly reevaporated before it is returned to the compressor in order to avoid injury to the apparatus and to operation personnel who may be near at hand. The present invention is designed to accomplish hot gas defrosting of the evaporator while fulfilling the just stated requirements to a high and very satisfactory degree.

Referring now to the form of the invention shown in Fig. 1, the compressor is denoted by 1, the condenser by 2, the receiver by 3, and the evaporator by 4. These parts may be of any well known or approved form, and they will not be further described herein, as their construction and functioning are thoroughly understood by those familiar with this industrial field and their particular construction constitutes no part of the present invention.

A hot gas conduit or pipe 5 connects the discharge of the compressor with the inlet of the condenser in the usual manner, and the refrigerant that is liquefied by the condenser and collected in the receiver is passed on to the evaporator through another conduit 6, which leads to the usual expansion valve 7 and from the said valve to the evaporator by another conduit 8. The outlet of the evaporator 4 is connected with a suction conduit 9 for leading the refrigerant back to the compressor, as will be hereinafter described. A feeler bulb 10 embraces the conduit 9 and communicates with expansion valve 7 by capillary tube 11 for controlling the action of the said valve, as is well understood in this art; and the evaporator 4 is provided with the customary fan 12 driven by motor 13.

A fluid tight casing 14 is suitably supported in

55

association with the other elements of the apparatus, and located therewithin by any suitable supports is an element 15 which is shown in the present instance as consisting of a coil of copper pipe filled with a heat holding substance such as a fusible salt of the proper crystalline form, for example, sodium sulphate (a satisfactory crystalline structure of sodium sulphate being ten molecules of water to one molecule of sodium sulphate), lead acetate, ferric nitrate, or calcium chloride; the ends of the pipe coil 15 being closed. Such substances are well known as having low fusion points and their function in this apparatus is to serve as a constant source of held heat. Sodium sulphate, which we prefer for this purpose, has a fusion or melting point of about 93° F. and, when its temperature is reduced a single degree by transfer of heat the amount of heat transferred is equal to about 90 B. t. u. per pound of the salt. The other substances named are capable of fusing in a similar manner but have different fusion points.

One end of casing 14 has an orifice 16 formed therein through which passes the end of suction conduit 9 with a fluid tight fit, a suitable stuffing box (not shown) being provided for this purpose if necessary. The extremity of said conduit 9 is downwardly turned, as indicated at 17, in order to discharge the fluid passing therethrough into the lower part of casing 14. Another orifice 18 is formed in the said end of casing 14 for similarly accommodating a continuation 19 of the suction conduit 9 which leads to the inlet of the compressor 1, as indicated at 20. The extremity of conduit 19 within the casing 14 extends substantially to the opposite end of the casing and is upwardly turned, as indicated at 21, so as to draw from the upper portion of the casing. It will be observed that a part of the suction conduit as it approaches the casing 14, which part is denoted by 22, lies alongside in contact, or at least in heat exchange relation with, a part of the hot gas compressor discharge conduit, which part is denoted by 23; whereby the said part 22 of the suction conduit, and the fluid passing therethrough, are heated by the part 23 of the hot gas line as the fluid flows from evaporator 4 to casing 14 so that the fluid may attain a temperature adequate to fuse the substance within coil 15.

A branch conduit 24 leads from the compressor hot gas refrigerant discharge conduit 5 to the drip pan coil 25 of the evaporator 4 and therefrom through another conduit 26 to conduit 8 at a point intermediate expansion valve 7 and the evaporator. In the said conduit 24 is positioned a solenoid valve 27 which is in electric connection with a source of current and a timing device (not shown but of any well known or approved form) for the purpose of periodically opening and closing the said valve. It will be clear that, when the valve 27 is opened, the hot gas from the compressor discharge will pass through conduits 24, 26 and 8 directly to the drip pan coil and evaporator coil of the evaporator 4, instead of passing through the condenser 2, and that the said hot gas thus passing directly to the evaporator will serve to defrost the said coils thereof in a well understood manner.

In normal operation, the solenoid valve 27 is closed, and the refrigerant gas from the discharge of compressor 1 passes through conduit 5, condenser 2, in which it is liquefied, receiver 3, conduit 6, expansion valve 7, and conduit 8 into the evaporator 4 where it serves the purpose of chilling the refrigeration chamber in which the

evaporator is located. This operation revaporizes the refrigerant and it flows through suction conduit 9 into casing 14 and from there through the portion 19 of the suction conduit to the inlet 20 of compressor 1. As this fluid flowing through the suction conduit from evaporator to compressor is in the form of gas or vapor, it will at once rise from the discharge 17 within the casing 14 to the intake 21 without being substantially affected by the heat holding substance in coil 15. However, if there is any liquid entrained with this gas, it will be vaporized by reason of the contact or juxtaposition of the part 22 of the suction conduit 9 with the part 23 of the hot gas discharge conduit as well as by the heat within casing 14 due to the presence therein of the heat holding substance.

When a defrosting period arrives, solenoid valve 27 will be opened by the automatic electric timer (not shown) and the hot refrigerant gas will then pass from the compressor discharge directly to the evaporator, as hereinabove described, for defrosting the latter. This defrosting step will liquefy the gas, at least in large part, so that the fluid returning through suction conduit 9 will be mainly, if not entirely, in liquid form. This liquid will, however, be revaporized in part by the heat exchange relationship of the portion 22 of the suction conduit with the portion 23 of the hot gas conduit, but chiefly by heat transferred to the liquid refrigerant by the heat holding substance in coil 15. The liquid flowing from outlet 17 will drop to the bottom of the casing 14 where it will be vaporized by the coil 15, following which the vapor will rise and be drawn in through inlet 21 of portion 19 of the suction conduit and carried back to the inlet of the compressor. The heat content of the substance in coil 15 is maintained by the fact that, during normal refrigerating periods, the refrigerant vapor returning from the evaporator through suction conduit 9 passes in heat exchange relationship with a portion of the hot gas conduit from the compressor discharge and thus picks up sufficient heat which is imparted to the coil 15 when the gas is emitted from outlet 17.

It should be observed that, as will be clear to those familiar with this industry, the electric timer for controlling solenoid valve 27 may be set to become effective at any predetermined spacing of periods and for any predetermined duration; and that it will also be electrically connected with motor 13 so that the evaporator fan 12, which is in operation during refrigeration periods for circulating air, will be stopped during defrosting periods when solenoid valve 27 is opened. It may also be mentioned that a pipe 28 is connected with the drip pan of the evaporator 4 in order to drain off to a sewer or other disposal point the water received by the drip pan during defrosting, the said pipe 28 being in practice positioned close enough to pipe 24 to establish heat exchange relation and prevent freezing.

Turning now to the modified form of the invention shown in Fig. 2, the compressor 1, condenser 2, receiver 3, evaporator 4, conduit 6, expansion valve 7, conduit 8, suction conduit 9, feeler bulb 10, capillary tube 11, fan 12, motor 13, suction conduit portion 19, drip pan coil 25, conduit 26, solenoid valve 27, and drip pan pipe 28, are the same and function in the same way as the corresponding parts shown in Fig. 1 and hereinabove described.

The casing 14 and the heat holding coil are also substantially the same in construction as in

the form shown in Fig. 1, but there is an important difference in that two of the heat holding coils, here denoted by 14a, 15b, are positioned in the casing, and the compressor hot gas discharge conduit, here marked 29 in the modified form shown in Fig. 2, is intertwined with the said heat holding coils, as indicated at 30, within casing 14 so that, during normal refrigerating periods, heat from the said hot gas conduit is imparted to the heat holding substance within the coils. Following its intertwining with the heat holding coils, the hot gas line passes out of the casing 14 and to the condenser 2. The orifices 31 and 32, through which the hot gas line 29 enters and leaves casing 14, may be provided with stuffing boxes (not shown) or any other suitable means for rendering them fluid tight.

In both forms of the invention the casing 14 is provided with a drain pipe 33 fitted with a strainer 34 that is connected by a capillary tube 35 with suction conduit 19, whereby any oil that may accumulate within casing 14 is returned to the oil sump of the compressor 1.

The hot gas defrosting conduit is denoted by 36 in the modified form of Fig. 2 and branches off from hot gas conduit 29 before the latter enters the condenser 2. This defrosting conduit is shown as provided with a strainer 31, which may also be inserted in the conduit 24 of the form shown in Fig. 1, if desired.

The operation of the form of the invention shown in Fig. 2 is the same as that of the form shown in Fig. 1 except that the two heat holding coils 15a, 15b, of the form shown in Fig. 2 are directly heated by the intertwining coil of the hot gas conduit 29, instead of being heated by the part 22 of the suction conduit 9 which lies against part 23 of the hot gas line in the form of Fig. 1.

Referring to both forms of the invention, the inlets and outlets 17 and 21 may be soldered to the interior of the casing 14, and the coils within the said casing may also be soldered to the casing or to a plate or the like lying on the bottom of the casing and therewithin; or the said coils may be held in position by radiating arms or brackets connecting them with the interior of the casing, or by any other satisfactory holding devices. As this provision constitutes no part of the present invention and is well within the understanding and skill of an ordinary mechanic, there is deemed to be no occasion to illustrate the same in the accompanying drawings. Also referring to both forms of the invention, a manually operated metering valve 38 may be inserted in conduit 6, if desired, for controlling the flow of refrigerant from the receiver 3 to the expansion valve 7.

We desire it to be understood that various changes may be resorted to in the form, construction, arrangement and material of the several parts without departing from the spirit or scope of the invention, and hence we do not intend to be limited to the details herein shown or described except as they may be included in the claims or be required by disclosures of the prior art.

What we claim is:

1. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suction conduit connecting the outlet of the evaporator

with the inlet of the compressor for returning refrigerant from the former to the latter, a casing positioned in the said suction conduit, and a fusible heat holding substance within said casing, the parts being so constructed and arranged that the refrigerant flowing through the suction line empties into the casing and surrounds the said heat holding substance as a fluid in heat exchange relation therewith while passing through said casing.

2. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suction conduit connecting the outlet of the evaporator with the inlet of the compressor for returning refrigerant from the former to the latter, a casing positioned in the said suction conduit, a portion of the suction conduit intermediate the evaporator and said casing being in heat exchange relation with the hot gas conduit that connects the discharge of the compressor with the condenser, and a fusible heat holding substance within said casing, the parts being so constructed and arranged that the refrigerant flowing through the suction line surrounds the said heat holding substance in heat exchange relation therewith while passing through said casing.

3. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suction conduit connecting the outlet of the evaporator with the inlet of the compressor for returning refrigerant from the former to the latter, a casing positioned in the said suction conduit, and a fusible heat holding substance within said casing contained in at least one hollow unit composed of heat conducting material, the parts being so constructed and arranged that the refrigerant flowing through the suction line empties into the casing and surrounds the said hollow unit in heat exchange relation therewith while passing through said casing.

4. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suction conduit connecting the outlet of the evaporator with the inlet of the compressor for returning refrigerant from the former to the latter, a casing positioned in the said suction conduit, and a fusible heat holding substance within said casing contained in at least one pipe coil composed of heat conducting material, the parts being so constructed and arranged that the refrigerant flowing through the suction line surrounds the said heat holding substance in heat exchange relation therewith while passing through said casing.

5. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suc-

tion conduit connecting the outlet of the evaporator with the inlet of the compressor for returning refrigerant from the former to the latter, a casing positioned in said suction conduit with the suction conduit entering the casing at a lower part thereof and leaving the casing at an upper part thereof, and a fusible heat holding substance positioned within said casing intermediate the points at which the suction conduit enters and leaves the casing, the parts being so constructed and arranged that the refrigerant flowing through the suction line surrounds the said heat holding substance in heat exchange relation therewith while passing through said casing from its point of entry to its point of leaving.

6. Refrigerating apparatus comprising, a compressor, a condenser, an evaporator, a conduit connecting the discharge of the compressor with the condenser and with the evaporator for conducting hot gas to the inlet of the condenser during refrigerating periods and to the inlet of the evaporator during defrosting periods, a suction conduit connecting the outlet of the evaporator with the inlet of the compressor for returning refrigerant from the former to the latter, a casing positioned in the said suction conduit, a portion of the hot gas conduit intermediate the compressor and the condenser being located within the casing, and a fusible heat holding substance also within said casing, the parts being so constructed and arranged that the refrigerant flowing through the suction line empties into the casing and surrounds the said heat holding substance and the said portion of the hot gas conduit as a fluid in heat exchange relation therewith while passing through said casing.
